THREAD GUIDING MECHANISM

Mathias Pedersen, Brooklyn, N. Y., assignor to
American Machine and Foundry Company, a
corporation of New Jersey

Application May 24, 1945, Serial No. 595,498

20 Claims. (Cl. 112—171)

1

This invention relates to sewing machines and more particularly to sewing machines of the over and under or running stitch type which utilizes a pair of opposed needle bars positioned on opposite sides of a work supporting table, and provided with means for gripping and projecting a double pointed needle having an eye located between its ends and a thread back and forth through material to be sewed.

In the operation of this type of machine it has been found that because of differences in the characteristics of the types of thread available, it is difficult to always insure that the thread will be properly positioned with respect to the instrumentalities of the machine which coact with the needle bars, the needle and the thread handling elements in handling the thread for proper sewing without breakage of the thread or the needle or both during operation of the machine.

With some kinds of thread there is little or no trouble in the proper operation of the machine. With other threads, such as "hard or right twist," cotton thread, and substitute threads now available, it has been found that in the formation of loops above and below the work supporting table there is a tendency for the thread to curl around the needle or form irregular loops which are positioned out of the paths of travel of the looper and the thread puller, respectively. These unsatisfactory characteristics of the thread cause improper operation of the machine and thread and needle breakage. The mechanism comprising the present invention makes possible the use of substantially any kind of thread with a minimum of stoppage or breakage of thread or needles.

In the operation of this type of machine, loops are formed alternately above and below the work as the result of the movements of the needle bars in projecting a threaded needle with a thread having a loose and a fixed end back and forth through the work. The machine is provided with an upper looper which engages the loops of thread formed above the work in order to pull slack and support the thread above the work and a thread puller which engages loops formed beneath the work table and pulls the loose end of the thread over the looper and through the work.

The operations of the looper and the thread puller are such that if the loops of thread above and below the work are not properly disposed in planes substantially at right angles to the path of movement of the looper and the thread puller, the looper will be unable to engage the loop of thread above the work, provide slack in the thread and support the engaged portion of the

2

thread during the operation of the thread puller. So also the thread puller will not be able to engage a portion of the loop beneath the work table in order to pull the loose end of the thread over the looper and through the work.

According to my invention there are provided devices which cooperate with the looper and the thread puller for insuring that each loop formed will be properly positioned and so held with respect to the paths of motion of the looper and the thread puller that at all times that portion of each loop of thread which is to be engaged by the looper and the thread puller is so engaged with the result that the operation of the machine is effected without interruption or thread or needle breakage.

The mechanism of the present invention relates to improvements for use on a sewing machine of the general type disclosed in Johnson Patent No. 2,368,066, issued January 23, 1945, and Johnson co-pending application, Serial No. 355,738, filed September 7, 1940, for Sewing Machine, now Patent No. 2,386,800, issued October 16, 1945. Although this mechanism is designed primarily for use with a machine of the type indicated above, its use is not so limited because it can find ready application in a sewing machine which requires positive stabilization and positioning of loops of thread during its operation.

It is an object of my invention to provide thread handling mechanisms for use with a sewing machine in positioning and maintaining loops of thread properly located in order that the operation of a sewing machine may be carried out with a minimum of thread or needle breakage.

It is a further object of my invention to provide a loop engaging member coacting with the looper of a sewing machine having opposed alternately reciprocating needle bars which project a double pointed needle and a thread having a loose and a fixed end back and forth through work to be sewed in order to insure that on each operation of the looper a predetermined portion of a loop of thread will be engaged and properly handled.

It is a further object of my invention to provide a loop disposing and positioning mechanism coacting with the lower needle bar of a sewing machine of the type described which functions to engage and stabilize the position of a loop of thread formed by the operation of the lower needle bar in order to insure that the thread puller will engage a predetermined portion of a loop of thread during each cycle of its operation.

It is a further object of my invention to provide

thread loop stabilizing and positioning mechanisms which coact with the thread looper operative adjacent the upper needle bar and the thread puller operative adjacent the lower needle bar of a machine of the type described herein and which function to maintain predetermined portions of loops of thread properly positioned with respect to the paths of motion of the looper and the thread puller so that at all times during the operation of the looper and the thread puller the loops of thread are engaged by these elements.

With these and other objects not specifically mentioned in view, the invention consists in certain combinations and constructions which will be hereinafter fully described, and then set forth in the claims hereunto appended.

In the accompanying drawings, which form a part of this specification, and wherein the several reference characters designate the same or like elements:

Figure 1 is a partial assembly view, partly in section, showing the relation between the needle actuating bars, thread handling mechanisms and the loop positioning and stabilizing mechanisms forming the invention;

Figure 2 is a side view showing diagrammatically the upper loop positioning mechanism in operative relation with respect to the looper, and the lower loop stabilizing and positioning means in inoperative position;

Figure 3 is a similar view showing the position of the lower loop stabilizing and positioning mechanism in operative relation with respect to the thread puller which is about to engage a properly positioned loop of thread;

Figure 4 is a front view illustrating somewhat diagrammatically the manner in which the upper loop positioning mechanism coacts with the looper shortly before its engagement with the looper;

Figure 5 is a plan view taken on line 5—5 of Figure 2;

Figure 6 is a diagrammatic sectional perspective view illustrating the lower loop stabilizing and positioning members in operative position and some of the operating mechanism therefor; and

Figure 7 is a diagrammatic plan view partly in section showing the mechanism illustrated in Figure 6 at a later stage in its cycle of operation.

Referring to the drawings, in Figure 1 there is shown a partial assembly view, partly in section disclosing the general structural and operative relationship between the mechanism constituting the invention and a sewing machine of the type shown in the above referred to Johnson Patent No. 2,368,800.

The machine is provided with a center support frame 30 and a combination end frame and housing 31, the frames being secured to and spaced from each other by suitable supporting members (not shown) which in turn are secured to the pedestal of the machine (not shown). A work supporting table 35 is suitably attached to a bracket (not shown) which in turn is secured to the machine frame in any desired manner.

The drive of the machine is effected by a pulley 37 driven by a belt 38 which also runs over a pulley (not shown) integral with a suitable clutch driven from a motor (not shown) in the same manner as disclosed in Johnson Patent No. 2,368,066. Since this mechanism forms no part of the invention, further details are omitted in the interest of brevity.

Pulley 37 is secured to the hub 40 of a gear

41 rotating about a stationary stud 42 fastened to the wall of frame 31 by screws 43. A hand wheel 44 secured to pulley 37 is provided to permit manual turning of the machine. A cam 39 is formed integral with and on the inside face of pulley 37. Cam 39 is provided with a cam track 45 engaging cam followers 46, 47 positioned at diametrically opposite points of the cam and mounted on arms 48, 49 formed on the rear ends of oscillating levers 50, and 51. Levers 50, 51 are pivotally mounted on shafts 52, 53, respectively, shaft 52 being supported at one end in a hub 54 of a bracket 55 secured to wall member 31 and at its other end being supported in a lug 56 secured to a bridge (not shown) of frame 31. One end of shaft 53 is supported in a hub 58 of a bracket 59 fastened to frame 31; its other end is supported in a hub 6 of a bracket 61 suitably attached to member 31.

20 An upper needle bar designated generally 63 and a lower needle bar indicated generally 64 (Figures 1, 2, 3, 4 and 6) arranged in opposed axial alignment on opposite sides of work supporting table 35 are provided with actuator members 65 connected to extending arms 66 and 67 at the forward ends of their respective oscillating levers 50, 51 whereby to convert the oscillating motion of levers 50, 51 into vertical reciprocating motion of the needle bars back and forth relative to table 35. The upper needle bar 63 is guided in bushings carried by lug 70 suitably attached to the forward end of the machine frame 31. The lower needle bar 64 is guided in bushings formed in lugs 72, 73 suitably supported on the machine frame 31.

25 The actuator members 65 are held in place on the respective needle bars 63, 64 by suitable lock nuts 75 (as shown in Figure 1). Vertically extending portion 76 of each member 65 is provided with a track 77 in which slides a rectangular block 78 carried by studs (not shown) fixed on the ends of arms 66, 67. The sliding blocks 78 provide means for converting the oscillating motion of arms 66, 67 into the desired vertical reciprocating motion of needle bars 63, 64.

30 The needle bars are similar in construction to those disclosed and described in co-pending Johnson application, Serial No. 448,189, filed June 24, 1942, now Patent No. 2,402,251, issued June 18, 1946. Each needle bar 63 and 64 is provided with a suitable chuck including needle grippers and operating mechanism therefor for grasping and releasing one end of a double pointed needle at the proper time during the operation of the machine. Since the specific construction of the needle bars forms no part of this invention, further details and description is considered unnecessary.

35 It will be understood by those skilled in the art that in this type of sewing machine the needle 81 is alternately grasped in the chuck of each needle bar. The action is such that as the lower needle bar 64 projects the needle upwardly through the work, it passes through an opening 65 in the lower end of the shell 91 of the upper needle bar 63 a predetermined distance. In the continued operation of the machine, the end of the needle gripped by the lower needle bar is released and the upper end of the needle is gripped by the upper bar 63 and pulled thereby through the work. On the next downward movement of the upper needle bar 63, the point of the needle being projected downwardly through the work to form the next stitch is passed through an opening in shell 91 of the lower needle bar

where it is gripped and pulled through the work thereby, after it is released from the upper needle bar.

Work feeding and presser foot mechanism of the same general type as that shown in the above referred to patent, No. 2,386,800, can be used for feeding the work along the table 35 and past the needle 81. This mechanism can consist of a work feeding bar 123 provided with a feeding dog 122 mounted for movement in a closed unidirectional path beneath the work table 35 and projecting upwardly through an elongated aperture in the table 35 into cooperating feeding engagement with a presser foot 120 and an upper work feeding foot 121 constructed and operated in the same manner as disclosed in Patent No. 2,386,800. Since the specific construction of this mechanism forms no part of the invention, further detailed description and showing is deemed unnecessary. As mentioned hereinabove, pulley 37 is driven by means of a belt 38 running over a clutch (not shown).

In order to operate the machine and drive pulley 37, there is provided a manually operated treadle (not shown) similar to that shown in the above referred to Johnson Patent No. 2,368,066 for transferring the drive from the motor to pulley 37, and hence through the gear train 41, 151, 226, 229, 231 and 232 driving the several instrumentalities described hereinafter. A manually operated treadle (not shown) may also be employed for raising and lowering the presser foot 120 in order to position work for sewing or removal from table 35.

A looper cam 170 (Figure 1) secured to hub 40 is tracked by a cam follower 171 which is mounted on a stud 172 carried by a lever 173 secured to a cross shaft 174 suitably mounted at one end in frame 31 and its other end in a hub 179 of a bracket (not shown) fastened to a portion of the bridge section of the machine frame. Cam follower 171 is held in engagement with cam 170 by means of a spring 175 which is stretched between a post 176 in lever 173 and a post (not shown) extending from housing 31.

Secured to shaft 174 adjacent and in front of the upper needle bar 63 is a looper arm 181 provided at its lower end with a pointed finger or shoe 182 and a thread guide roller 183 which together with a tension finger 184 mounted adjacent the upper needle bar and substantially at the opposite side thereof with respect to looper arm 181 act upon the thread in a manner to be described hereinafter. The finger 184 is secured to arm 185 loosely mounted on shaft 174, the hub of arm 185 being mounted between fiber washers 186 serving to maintain frictional contact with looper arm 181, the frictional connection being maintained by the pressure of a compression spring 187 positioned between a collar 188 fixed to shaft 174 and a collar 189 loosely mounted on shaft 174. The finger 184 is normally held inoperative by a stop screw 190 adapted to engage a pin 191 projecting from arm 185, screw 190 being adjustably fastened in a wing 192 of a holder 193 secured to member 71, forming a part of the bridge frame (not shown).

When the needle is transferred from the lower needle bar 64 to the upper needle bar 63, the latter grasps the needle and due to the continued rotation of cam 39 and the actuation of lever 50 moves to its up-position. The looper arm 181 by means of its cam 170 is moved counterclockwise (as shown in Figures 2 and 3) towards finger 184 which normally is positioned to the right of

the upper needle bar 63, as indicated in Figure 3. Arm 181, under the influence of cam 170, continues to travel until the point of finger 182 is about an alignment with the tip of finger 184 in which position it dwells momentarily. Continued rotation of cam 39 and the coaction between cam 45 and cam follower 46 on arm 48 causes the needle bar 63 to descend slightly and dwell and in so doing a loop is formed in the thread. Substantially simultaneously arm 181 under the actuation of cam 170 and finger 184 advance in unison in a clockwise direction; shoe 182 on arm 181 engages the front portion L₁ of the loop in the thread (Figures 4 and 5) while finger 184 engages the rear loop portion L₂ (Figures 2, 4 and 5). As shown in Figure 2, finger 184 comes to rest with loop portion L₂ displaced out of the path of travel of the needle 81, and any danger of splitting or damaging by the needle of that portion of the thread is substantially eliminated. Looper arm 181 continues to move in a clockwise direction and the portion L₁ of the loop which has been guided by shoe 182 onto roller 183 is displaced to substantially the position illustrated in Figure 2 whereupon the upper needle bar 63 completes its downward stroke and delivers the needle to the lower needle bar 64. Continued rotation of cam 170 causes the looper arm 181 to move in a counterclockwise direction towards upper needle bar 63 where it dwells in substantially the position shown in Figure 3 during the formation of the next loop beneath the work and the pulling of the loose end of the thread over roller 183 and through the work in completing the stitch. The forward advance or clockwise movement of finger 184 is stopped when pin 191 abuts stop screw 190 adjustably mounted in wing 192 of holder 193 suitably fastened to frame member 71 while at the same time the looper arm 181 is operating as described above. Upon completion of the operation of the thread puller 202 in pulling the loose end of the thread through the work, the looper arm 181 and the finger 184 are moved counterclockwise to their inoperative positions where they remain pending the next downward movement of the upper needle bar 63.

During the operation of this type of machine, there is a tendency for loop portions L₁ and L₂ of the upper loop and portions L₃, L₄ of the lower loop to curl about the needle 81 in such a way that these loop portions are not properly positioned in the path of travel of shoe 182 on looper arm 181 or finger 184, or thread puller 202. When a loop portion of the thread is not properly disposed and supported with respect to the needle or the thread handling elements mentioned, breakage of the thread or the needle or both may take place.

In order to overcome such undesirable features, which result in loss of time, machine stoppage, and replacement of needles, there are provided thread stabilizing and positioning mechanisms which coact with the upper and lower needle bars and thread handling elements and make possible the use of all kinds of thread with a minimum of breakage of thread or needles. The mechanism which coacts with the upper needle bar and the looper 181 and finger 184 is designated generally 159 and consists of a lever 160 pivotally supported on a pin 162 mounted in an extension 163 formed on looper arm 181. Lever 160 is provided with a flat plate 164 extending at an angle to the lever as shown in Figure 4. A relatively light spring 166, positioned about pin 162 and provided with an end 167 bearing against

lever 160 and an end 168 engaging a slot in extension 163, urges the lever 160 toward the looper arm 181. The operation of the thread stabilizing and positioning member 159 is such that while the end of looper arm 181 is located to the right of upper needle bar 63, (not shown) plate 164 is held by spring 166 against needle 81 away from stop 181a on looper arm 181. However, when the point of shoe 182 moves clockwise past the center of needle bar 63 to the position shown in Figure 2 or occupies a dwell position to the left of needle 81, as viewed in Figure 2, spring 166 holds plate 164 against stop 181a on looper arm 181. However, when the upper needle bar 63 has moved downwardly to the position shown in Figure 4 and formed the loop having loop portions L₁, L₂, plate 164 will operate in conjunction with the needle to form a support for these loop portions and prevent them from curling around the needle. In other words, plate 164 tends to maintain loop portions L₁, L₂, in a plane substantially at right angles to the path of movement of shoe 182 on looper arm 181 so that as the looper arm 181 swings or moves in its clockwise direction, loop portion L₁ is always positioned directly in the path of movement of shoe 182, and loop portion L₂ is located properly for engagement by finger 184. Movement of looper arm 181 in a clockwise direction beyond the path of movement of needle 81 through the work, makes it possible for spring 166 to swing plate 164 into a position closely adjacent or in engagement with the pointed end of shoe 182 so that lateral movement or escape of the loop portion L₁ from roller 183 is substantially prevented. Plate 164 is of a length sufficient to provide support for loops L₁ and L₂, and prevent substantial twisting thereof out of the paths of shoe 182 and finger 184 regardless of whether right or left twist thread is used.

In the illustrated embodiment, the relationship between the end 181a of arm 181 and plate 164 is such that as the looper shoe 182 moves past needle 81 and plate 164 is moved by spring 166 towards shoe 182, plate 164 engages the end portion 181a of the arm 181, acts as a stop and holds plate 164 a short distance away from the pointed end of shoe 182. This prevents a rapid movement of plate 164 against the end of shoe 182 which might result in breakage or a pitting of the plate.

The operation of looper arm 181 and finger 184 as mentioned above is the same as the operation of like elements disclosed in the above referred to Johnson patent, No. 2,386,800.

With needle 81 gripped in the lower needle bar 64, the continued operation of cam 39 and the coaction of cam follower 47 with cam track 45 causes the needle bar 64 to descend to its down position and pull the thread through the work whereupon it immediately ascends slightly and dwells, this slight upward movement tending to form a loop in the thread with loop portions L₃, L₄ disposed somewhat as shown in Figure 6.

Figures 1, 3, 6 and 7 show the thread loop stabilizing and positioning mechanism for insuring that loop portion L₃ is always maintained in a plane substantially at right angles to the path of movement of the thread puller 202 so that in each cycle of operation of the thread puller 202, loop portion L₃ is so located with respect to the thread puller that it is always engaged and the loose end of the thread pulled through the work and disposed about drum 309.

The thread puller 202 which is operated in

proper timed relation with respect to the other elements of the machine is mounted on lever 246 secured to shaft 245 mounted in support 210 secured to frame 30. Shaft 245 has secured thereto a lever 244 provided with a cam follower 243 positioned between spaced bars 240 and 241 mounted on gear 232 forming a runway or track so that during the rotation of gear 232 rotary motion is imparted to arm 246. The movement of thread puller 202 carried by arm 246 is such that as the puller 202 advances its forward pointed end engages the positioned and supported loop portion L₃ formed in the thread (Figures 3, 6 and 7). Thread puller 202 moves slowly into engagement with loop portion L₃ as it starts to pull the loose end of the thread through the work. It will be seen that thread puller 202 does not act with such quickness in starting the pull of the thread through the work so as to tend to fray out the thread after a number of pulls or with a tendency to jerk and break the thread. However, after the pull is actually started, the movement of arm 246 and puller 202 increases speed when danger of thread breakage is passed. The action of the thread puller, therefore, is to pull the loose end of the thread through the work with gradually increasing speed from approximately the time it first picks up the thread loop portion L₃ and as it travels with the thread to dispose it about drum 309. The construction and mounting of arm 246, puller 202 and drum 309 are the same as disclosed in Johnson Patent No. 2,386,800, and further detailed description thereof is deemed unnecessary.

A tensioning finger (not shown) coacts with the thread puller to dispose the thread properly out of the path of the needle so that at the time of transfer of the needle from needle bar 64 to needle bar 63, the thread is held out of the path of the needle and properly tensioned. This mechanism forms no part of the present invention and further description and showing thereof is not considered necessary.

Operating in conjunction with the thread puller 202 and drum 309 is a thread trap 306 and a pair of laterally movable gripping jaws 288, 289 which engage the thread, move it laterally or rearwardly (as seen in Figure 2) to position a portion of the thread in the trap 306 out of the path of the needle and the moving thread puller. This mechanism, which is the same as that disclosed in the above mentioned Johnson Patent No. 2,386,800 is not shown or described in greater detail because it forms no specific part of the present invention.

In order to prevent excess tensioning of the fixed portion of the thread in the work during the operation of the thread puller 202 there is provided thread gripping mechanism similar to that shown in the above referred to Johnson Patent No. 2,386,800. This mechanism consists of gripper arms 200, 201 operated by a cam 203 fixed to shaft 205 driven by a gear 226 fixed thereto meshing with gear 229, which gear in turn meshes with gear 231. Cam 203 has a cam track 199 in which runs a cam follower 206 on a cam lever 207 mounted on stud 208 carried by a holder 209 fastened to support 210 attached to frame 30. The upper end of cam lever 207 is provided with an open end yoke 211 adapted to engage a block 212 pivoted in a bar 213 sliding in block member 214 suitably secured to the frame of the machine. Gripper jaws 200 and 201 are mounted for pivotal movement on pins 216 in block 214; the jaws are provided with extensions 219 in which are

mounted cam followers 217 which are located in cam tracks 215 formed in slide member 213. It will be seen that the rotation of cam 203 causes a reciprocation of slide 213 and an opening and closing of jaws 200, 201 to grip and release loop portion L₄ or the fixed portion of the thread.

In order to assure that the loop portion L₃ is always properly positioned and maintained in proper location for engagement by thread puller 202 there is provided a pair of clamp members or plates 250 pivotally mounted on pins 252 fixed in drum 309 (see Figures 1, 6 and 7). Plates 250 are provided with downwardly extending angular projections 251 which are engaged by the tips 221 of gripper jaws 200, 201 so that as the jaws open or move to inoperative positions, the plates are also opened and moved to the positions indicated in dotted lines in Figure 7 in order to allow the lower needle bar 64 to continue its upward movement and project the needle 81 through the work and deliver it to the upper needle bar 63. Angular abutments 254 formed on the rear faces of plates 250 limit the extent of opening movement of plates 250. A spring 253 having its ends secured to plates 250 maintain projections 251 in engagement with gripper jaw tips 221, and urge the plates 250 into closed or loop supporting position, as shown in Figures 6 and 7. As jaws 200, 201, as indicated in dotted lines in Figure 7, begin to move to closed position relative to needle 81, spring 253 causes plates 250 to begin to close. The ratio of length of gripper jaws 200, 201 to the length of plates 250 is such that plates 250 reach their closed thread loop stabilizing position, as shown in full lines in Figure 7, in advance of gripper jaws 200, 201.

In order to control the inward movement of plates 250 by spring 253 to their loop holding positions (Figures 6 and 7), and prevent damage thereto by striking against the needle, such as the formation of grooves in those portions of the plate which move into adjacency with the needle, there are provided collars 260, having flat faces 262, adjustably mounted on pivot pins 252 and secured in adjusted positions by set screws 264. Collars 260 can be so adjusted (as shown in Figure 7) that portions thereof project outwardly beyond plates 250 and act as stops to hold plates 250 spaced apart relative to needle 81. Therefore, when plates 250 are in closed position (as shown in Figures 6 and 7), there can be free upward movement of needle 81 therebetween and the proper formation of lower loops having portions L₃, L₄.

The timing of the machine is such that cam 203 causes cam slide 213 to begin the movement of jaws 200, 201 during the final downward movement of needle bar 63 and as the needle 81 is transferred to lower needle bar 64, slowly into closing or thread gripping position. This operation causes plates 250 to be moved by spring 253 into closed or thread loop supporting position as limited by collars 260 prior to the next upward movement of lower needle bar 64 and needle 81. Therefore, as the needle moves upwardly to form a lower loop, it passes between the closed plates 250 and the loop portions L₃ and L₄ which extend outwardly from the needle, are formed, and positioned between plates 250 in the manner shown in Figures 6 and 7. Because of this association the loop portions L₃, L₄ are stabilized and held properly located between the plates 250 and cannot twist angularly about the needle 81 as it moves upwardly between the plates. Before the loop portion L₃ is completely formed the

movement of slide 213 by cam 203 is completed and gripper jaws 200, 201 close against and grip loop portion L₄. Continued upward movement of the needle bar 64 causes a further expansion of loop portion L₃ to the position indicated in Figure 6 although if desired the timing can be such that the loop portion L₃ is completed formed before jaws 200, 201 grip loop portion L₄. It will be seen that the closed plates 250 control the final position of each loop portion L₃ formed and assure that each is located properly directly in the path of the movement of the thread puller 202 for engagement thereby, which is then moved by mechanism described hereinabove into engagement with loop portion L₃ and pulls the loose end of the thread over roller 183, through the work and lays it upon drum 309 in known manner. The upper surfaces of jaws 200, 201 are reduced in an amount substantially equal to the thickness of plates 250 in order that the plates may lie flush with the upper surface of the jaws when in closed position as indicated in Figure 7 in full lines and thereby neither interfere with nor obstruct any moving parts.

The invention above described may be varied in construction within the scope of the claims, for the particular device, selected to illustrate the invention, is but one of many possible concrete embodiments of the same. It is not, therefore, to be restricted to the precise details of the structure shown and described.

What I claim is:

1. In a sewing machine provided with a needle bar and a needle for projecting a thread through material to be sewed, mechanism for moving said bar to and from said work, a thread looper arm mounted adjacent said bar, a looper on said arm adapted to engage a loop formed in said thread, and a member carried by said arm being constructed and arranged to coact with said needle for positioning said loop for engagement by said looper.
2. In a sewing machine provided with a work supporting table, a needle bar and a needle for projecting a thread through material to be sewed, mechanism for moving said bar towards said material and forming a loop in a portion of said thread, a looper arm, a loop engaging shoe carried by said arm, and a resiliently mounted loop positioning member constructed and arranged to cooperate with said needle carried by said arm for maintaining said loop positioned in the path of movement of said shoe for engagement thereby.
3. In a sewing machine provided with a work supporting table, a needle bar and a needle for projecting a thread through material to be sewed, mechanism for moving said bar towards said material and forming a loop in a portion of said thread, a looper, a loop positioning member carried by said looper constructed and arranged to cooperate with said needle for maintaining said loop positioned for engagement by said looper, said member comprising a lever provided with a movable loop positioning plate, and means for moving said member into loop positioning position relative to said looper.

4. In a sewing machine provided with a work supporting table, a needle bar and a needle for projecting a thread through material to be sewed, mechanism for moving said bar towards said material and forming a loop in a portion of said thread, a looper arm, a loop engaging shoe carried by said arm, a resiliently mounted loop positioning member carried by said arm constructed and arranged to cooperate with said needle for main-

taining said loop positioned for engagement by said shoe, said member comprising a movable loop positioning plate, a mount on said arm for said plate, and means for moving said plate into operative relationship relative to said shoe.

5. In a sewing machine of the type described having a work supporting table and a vertically reciprocable needle bar mounted for movement to and from said table for projecting a needle and thread through material to be sewed, a thread engaging finger movably mounted adjacent one side of said bar, a looper mounted adjacent another side of said bar, mechanism for reciprocating said bar and forming a loop in said thread above said table as the bar and threaded needle travel towards said table, means for moving said finger to engage one portion of said loop, means for moving said looper to engage another portion of said loop, and a device constructed and arranged to cooperate with said needle for positioning said loop in the path of movement of said looper.

6. In a machine of the type described having a work supporting table and a reciprocable needle bar mounted for movement to and from said table for projecting a threaded needle through material to be sewed, a thread engaging finger movably mounted adjacent one side of said bar, a looper mounted adjacent an opposite side of said bar, mechanism for reciprocating said bar and forming a loop in said thread above said table on each movement of said threaded needle towards said material, said loop having a rear portion and a front portion extending generally in a plane substantially at right angles to the path of movement of said material over said table, means for moving said finger to engage and displace said rear loop relative to said needle, means for moving said looper, and a device mounted on said looper constructed and arranged to cooperate with said needle for holding said front portion of said loop in position to be engaged by said looper.

7. The structure defined in claim 6 wherein said device comprises a movably mounted lever, a loop engaging plate on said lever, and resilient means for biasing said plate towards said looper.

8. In a sewing machine of the type provided with a work supporting table and opposed needle bars mounted on opposite sides of said table, mechanism for reciprocating said bars alternately to project a double pointed needle and a thread back and forth through said work to form stitches in said work and alternately form loops above and below said work, a thread looper mounted above said table, a device constructed and arranged to cooperate with said needle for maintaining loops in said thread above said table in position to be engaged by said looper, loop positioning means mounted beneath said table, a thread puller for engaging loops formed in said thread beneath said table and maintained in the path of movement of said puller, and mechanism for operating said device and last-named means in timed relation with the movements of said looper and thread puller.

9. In a sewing machine of the type having a work supporting table, and opposed needle bars mounted on opposite sides of said table, mechanism for reciprocating said bars alternately to project a double pointed needle and a thread back and forth through said work to form stitches in said work and alternately form loops above and below said work, a thread looper mounted above said table, a loop positioning device mounted on said looper, constructed and arranged to position

a portion of a loop above said work in the path of said looper, a thread puller located beneath said table, and loop positioning means coacting with said puller for positioning a portion of a loop formed beneath said table in the path of said puller for engagement thereby.

10. In a sewing machine of the type defined having opposed alternately reciprocating needle bars, and mechanism for alternately moving said bars to project a threaded double pointed needle back and forth through work to be sewed, a looper mounted adjacent one of said bars, a thread puller mounted adjacent said other bar, a loop positioning device to position a loop formed by the movement of one of said bars in the path of movement of said looper for engagement thereby, a second loop positioning device mounted adjacent said other bar, and means for operating said second device to maintain each loop formed by the movement of said second bar in the path of movement of said puller.

11. In a sewing machine provided with a work supporting table and a needle bar, mechanism for reciprocating said bar to project a needle and a thread having a loose and a fixed end through work to be sewed and to form loops in said thread, a thread puller, means for engaging and positioning loops formed in said thread in the path of movement of said puller, and means for driving said puller to cause it to engage each of said positioned loops and pull the loose end of the thread through the work.

12. In a sewing machine of the type having opposed alternately moving needle bars for projecting a double pointed needle and a thread having a loose and a fixed end back and forth through work to be sewed, a looper mounted adjacent one of said bars, a thread puller located adjacent the other of said bars, a loop positioning member constructed and arranged to support a loop formed in said thread above said work directly in the path of movement of said looper for engagement thereby, means for moving said looper into engagement with said supported loop to engage and support a portion of said thread, a loop engaging and positioning device for holding each loop formed adjacent said last-named needle bar in a plane substantially at right angles to the path of movement of said puller, and means for moving said puller into engagement with each loop supported by said device for pulling the loose end of said thread over said looper and through said work.

13. In a sewing machine of the type having opposed alternately moving needle bars for projecting a double pointed needle and a thread having a loose and a fixed end back and forth through work to be sewed, a looper mounted adjacent one of said bars, a thread puller located adjacent the other of said bars, a loop positioning member constructed and arranged to support a loop formed in said thread above said work directly in the path of movement of said looper for engagement thereby, means for moving said looper into engagement with said supported loop to pull and support a portion of said thread, a pair of pivotally mounted thread positioning jaws for engaging and positioning each loop formed adjacent said last-named needle bar in a plane substantially perpendicular to the path of movement of said puller, a pair of gripper jaws for holding the fixed end of said thread against excess tensioning in said work during the operation of said puller, connections between said positioning jaws and said gripper jaws for closing

13

said first-named jaws on said loop prior to the closing of said gripper jaws on said fixed end of said thread, and means for operating said gripper jaws.

14. In a sewing machine of the type having opposed alternately moving needle bars for projecting a double pointed needle and a thread having a loose and a fixed end back and forth through work to be sewed, a looper mounted adjacent one of said bars, a thread puller located adjacent the other of said bars, a loop positioning member constructed and arranged to support a loop formed in said thread above said work directly in the path of movement of said looper for engagement thereby, means for moving said looper into engagement with said supported loop to pull and support a portion of said thread, a thread receiving drum, a pair of thread positioning jaws for engaging and positioning each loop formed adjacent said last-named needle bars in a plane substantially perpendicular to the path of movement of said puller pivotally mounted on said drum, a pair of gripper jaws for holding the fixed end of said thread against excess tensioning in said work during the operation of said puller, connections between said positioning jaws and said gripper jaws for closing said first-named jaws on said loop prior to the closing of said gripper jaws on said fixed end of said thread, and means for operating said gripper jaws.

15. Thread loop positioning mechanism for a sewing machine having a thread supporting drum, opposed needle bars for projecting a needle and a thread having a loose and a fixed end back and forth through work to be sewed, comprising a pair of movably mounted thread engaging plates supported on said drum, a thread puller, mechanism for reciprocating said bars, to project said needle and thread through said work and form a loop in said thread during a portion of the operation of said mechanism, and means operative after the formation of a loop in said thread for closing said plates upon opposite sides of said loop.

16. Thread loop positioning mechanism for a sewing machine having a thread supporting drum, opposed needle bars for projecting a needle and a thread having a loose and a fixed end back and forth through work to be sewed, comprising a pair of pivotally mounted thread engaging plates supported by said drum, a thread puller, mechanism for reciprocating said bars to project said needle and thread through said work and form a loop in said thread during a portion of the operation of said mechanism, a thread puller, means operative after the formation of each loop for closing said plates against said loop to hold said loop in the path of said puller, and means for operating said puller for pulling the loose end of said thread through said work and disposing it upon said drum.

17. Thread loop positioning mechanism for a

14

sewing machine having a thread supporting drum, opposed needle bars for projecting a double pointed needle and a thread back and forth through work to be sewed, a pair of plates movably mounted on said drum, spring means normally urging said plates towards each other, thread grippers, mechanism for alternately reciprocating said bars and forming loops in said thread first on one face and then on the other face of said work, operating means for said grippers, and connections between said grippers and said plates for effecting a movement of said plates against opposite sides of a loop in advance of the gripping of a portion of said loop by said grippers.

18. In a thread loop positioning mechanism for a sewing machine, a thread supporting drum, means for forming a loop in a thread adjacent said drum, a traveling thread puller adapted to engage a portion of said loop, thread loop engaging and positioning members, and means for effecting movement of said members into engagement with said loop to position said loop in a plane substantially perpendicular to the path of movement of said puller.

19. In a sewing machine provided with a work supporting table and a needle bar, mechanism for reciprocating said bar to project a needle and a thread back and forth through work to be sewed, said mechanism being operative to form loops in said thread spaced from the surface of said work, a loop engaging device having a path of movement into engagement with said loops, means for engaging opposite sides of said loops and positioning said loops formed in said thread in a plane substantially perpendicular to the path of movement of said device, and means for operating said device to cause it to engage said positioned loops.

20. In a thread loop positioning device for a sewing machine having a work support and a reciprocating threaded needle, means for forming a loop in a thread spaced from work positioned on said support, and having a loop portion on opposite sides of said needle, a loop engaging member having a path of movement into engagement with said loop, means for engaging opposite sides of said thread forming said loop portions and positioning at least one of said loop portions in a plane substantially at right angles to the path of travel of said member, and means for moving said member to engage said loop portion of said loop of thread.
